CLAIM

The ornamental design for combined finger clip and cup holder for dental cleaning paste or the like, as shown and described.

DESCRIPTION

FIG. 1 is a reduced perspective view of a combined finger clip and cup holder for dental cleaning paste or the like showing my new design;

FIG. 2 is a front view thereof;

FIG. 3 is a side view thereof;

FIG. 4 is a top view thereof;

FIG. 5 is a bottom view thereof;

FIG. 6 is a reduced perspective view similar to FIG. 1, the cup being shown in broken lines for illustrative purposes only.

FIG. 1.

FIG. 6.

FIG. 2.

FIG. 3.

FIG. 4.

FIG. 5.
